PRINTING PLATE AND METHOD OF MAKING
THE SAME

Arthur B. Davis, Springfield, Ohio

Application August 22, 1935, Serial No. 37,319

5 Claims. (Cl. 41—25)

This invention relates generally to printing plates which constitute reproductions of the type surface of a type form, engraving or the like, and has more particular reference to the formation of printing plates composed in part of moldable material such as synthetic resin.

The general object of the invention is to provide a new and improved printing plate comprising a layer of resinous material having molded type projections and itself adhesively secured in the molding operation to the surface of an imperforate metal sheet by which the plate as a whole may be fastened properly to a printing press support.

Another object is to provide for the novel treatment of the printing plates during the molding operation to incorporate make-ready therein so that in the use of the plates in printing selected solid areas of the type will be emphasized and the pressure on selected high light areas relieved.

A further object is to provide a method of reproducing the type surfaces of original forms or engravings which provides for the elimination, in a novel manner, of the parts corresponding to the so-called "dead metal" ordinarily provided in the engraving.

Other objects and advantages of the invention will become apparent from the following detailed description taken in connection with the accompanying drawings, in which

Figure 1 is a perspective view of the improved printing plate in the process of attachment to a printing press cylinder.

Fig. 2 is a fragmentary sectional view of the printing plate attached to the cylinder.

Fig. 3 is a plan view of a make-ready sheet used in the treatment of the plate.

Fig. 4 is a plan view of a sheet used in connection with the removal of the resin from the "dead metal" areas of the plate.

Fig. 5 is a fragmentary perspective view of the mold from which the printing plate is made.

Fig. 6 is a fragmentary perspective view of an original type form or engraving to be reproduced.

Fig. 7 is a fragmentary perspective view of the mold with one form of make-ready sheet attached to the underside thereof.

Fig. 8 is a fragmentary sectional view illustrating the arrangement of the parts preparatory to the molding operation.

Fig. 9 is a perspective view of the finished plate illustrating the method of removing the resin from the non-type areas.

Fig. 10 is a view similar to Fig. 8 illustrating the method of forming a modified form of printing plate.

Fig. 11 is a fragmentary sectional view of the modified plate attached to a printing press cylinder.

Fig. 12 is an elevational view of the preferred form of make-ready sheet.

Fig. 13 is a section taken along the line 13—13 of Fig. 12.

The invention is susceptible of various modifications and therefore I do not, by the present exemplary disclosure, intend to limit the invention, but aim to cover all modifications and alternatives falling within the spirit and scope of the invention as expressed in the appended claims.

In the drawings, the invention is illustrated as applied to the formation of a printing plate 10 comprising areas 11 of molded resinous material adhesively secured to an imperforate metal mounting sheet 12 and having projections 13 standing out in relief and defining surfaces 14 corresponding to the characters or other configurations to be printed. The areas 11 may be composed wholly of resinous material or of a mixture of a base or filler ingredient combined with a resin binder. While any preferred moldable resinous material may be used, it is preferred, in order to permit the plate to be bent readily to the proper curvature, to employ a resin having thermoplastic characteristics such as that sold under the trade name of Vinylite.

The relatively flexible plate thus constructed may be attached to the printing press support or cylinder 16 through the medium of a backing or saddle which, for purposes of illustration, is shown as comprising two plate sections 17 and 18 hinged together at 19 and adapted to engage at their remote side edges with shoulders in the form of flanges 20 formed on the carrying sheet 12. The section 18 is adjustably secured against the surface of the cylinder 16 by clamps 21. When the narrower section 17 is swung downwardly against the cylinder with the plate 10 positioned as shown in Fig. 1, the flanges 20 will be spread apart and the plate stretched over the saddle, the free edge of the section 17 being later fastened down by means of clamps 22.

The printing surfaces of the plate above described constitutes a molded reproduction of the surfaces of an engraving 23 or other type form well known in the printing art. To obtain an accurate replica so that all of the dots for obtaining the different color shades may be repro-

duced accurately, a mold 24 formed from the engraving is used in molding the printing areas. For a purpose to appear later, the mold preferably comprises a layer 25 of ductile metal, such as lead, having cavities 26 therein corresponding to the type projections to be formed and attached through the medium of a sheet 27 of steel or other reinforcing material to a sheet 28 of ductile metal having a flat machined surface 29 disposed in a plane parallel to the roots of the type cavities. The mold may be formed in the manner described in my copending application Serial No. 736,222, filed July 20, 1934.

The plate molding operation is carried on in a suitable press preferably operated hydraulically and having platens 30 and 31 heated as by gas flames 32 to the temperature necessary for softening the resin ingredients to the degree required for molding. During molding, the mold is supported on the lower platen 31 and covered with a layer 33 of the resin ingredients sufficient in amount to more than fill all of the mold cavities when in the plastic state. The carrying sheet 12 may be fastened by a filler plate 34 against which the upper platen 30 acts. With the parts thus assembled, the platens are first maintained in close proximity to each other until the resin has been softened properly. Then the platens are moved together under pressure to compress the plastic ingredients to a thickness determined by bearers 35 after which the resin is allowed to set with the back surface of the sheet 12 thus accurately maintained in parallel relation to the type surfaces. Upon cooling, the finished plate may be stripped from the mold and thereafter bent readily to the proper curvature by reheating to a temperature sufficient to soften the resin slightly.

The surface of the carrying sheet 12 is treated in a manner such as to cause firm adherence of the plastic resin thereto so that the resin areas will not be displaced during bending of the plate or under the stresses applied thereto during printing. This may be accomplished by covering the surface of the sheet 12 with cloth 36 such as muslin to which the resin will adhere readily and which in turn may be cemented to the metal by means of a suitable adhesive such, for example, as water glass cement.

Provision is made for ready removal from the molded plate of those areas of the resinous material corresponding to the non-type or so-called "dead metal" areas 23^a of the engraving thereby avoiding the costly operation of routing out these areas to prepare the plate for use in printing. For this purpose, the invention contemplates the introduction between the resin ingredients 33 and the muslin surface of the sheet 12 of a parting medium corresponding in shape and position to the non-printing areas and acting during the molding operation to prevent the plastic resin material from coming into contact with the selected areas of the treated surface.

Herein this parting medium takes the form of a sheet 37 (Figs. 4 and 8) of manila paper cut out to form openings 38 corresponding in shape to but slightly larger than the type areas. To facilitate formation of this mask, a printed impression of the engraving 23 may be formed on the paper sheet 37 in a proving press and the printed areas then cut out to form the mask. The latter is secured detachably to the cloth covered surface of the carrying sheet 12 or placed in proper position above the resin ingredients 33 preparatory to molding. As indicated at 50, the resin adheres to the mask which, after molding, may be stripped

off from the carrying sheet. In this operation, the thin section 39 of the resin material immediately surrounding the type areas is first scored with a knife so that it will break readily as the thicker areas are bent away from the plate as illustrated in Fig. 9. Thus, in the finished plate, only the printing areas proper and the thin border 39 therearound remain on the cloth surface. Where there is a dead metal area 51 (Fig. 6) completely surrounded by type areas, the corresponding portion of the resin may be removed by applying a properly shaped piece 52 of paper (Fig. 4) to the resin layer or muslin sheet before the molding operation.

Where several similar printing plates are required, it is the present practice to provide for increasing the printing pressure on the so-called "solid" areas of the plate and relieving the pressure on the "high light" areas through the use during printing of make-ready sheets individual to the separate plates. The present invention contemplates a substantial reduction in the cost of the make-ready treatment of a series of duplicate plates through the association with the mold from which the plates are made of a single make-ready sheet which operates automatically during the molding of each plate to properly prepare the plates for printing and in effect incorporate the make-ready details in the plate itself. For this purpose, advantage is taken of the inherent flexibility possessed by the mold 24 when constructed as above described to enable the heights of the selected printing areas formed thereby to be varied relative to each other during the molding operation by the action of a built-up underlay 40 positioned against the flat back surface 29 of the mold.

As illustrated in Fig. 7, the underlay 40 is in the form of a paper sheet having indentations 41 therein disposed opposite the mold cavities 40 corresponding to "solid" printing areas upon which the pressure is to be increased during printing. Paper patches 42 may be secured to the underlay sheet opposite the cavities corresponding to the "high light" areas on which the printing pressure is to be relieved. During molding of the first plate, those parts of the mold which are in register with the underlay sheet will be supported by the latter while the parts opposite the indentations 41 will be depressed by flexure of the mold under the pressure to which it is subjected. Accordingly, the printing surfaces of the type formed in the depressed cavities will, in the finished plate, project a greater distance from the sheet 12 than the surrounding printing surfaces, this difference in the heights of the printing surfaces being determined by the depth of the indentations 41. Thus, in the use of the plate in printing, the pressure on the higher areas will be increased, and the "solids" corresponding to the size and shape of the depressions 41 will be emphasized properly. Similarly the printing pressure on selected "high light" areas may be reduced to the desired degree through the provision of the patches 42 of the proper size and shape. Under the molding pressure, these patches flex the mold and raise the roots of the type cavities in register therewith thereby causing the corresponding printing surfaces of the finished plate to be spaced closer to the sheet 12 than the surrounding surfaces.

Owing to the flexible and ductile character of the lead of which the mold is constructed, the printing areas of the finished plate which are affected by the action of the make-ready details 75

correspond accurately in size and shape to the indentations 41 and the patches 42. As a result, sufficient precision may be attained in the make-ready treatment to substantially avoid the necessity of any further treatment in the use of the plate in printing. The lead of the mold will of course take a set in the initial plate molding operation, but will nevertheless respond to changes in the underlay sheet that may be added subsequently.

To facilitate formation of the underlay 40 and proper location of the details, it is preferred to build up the details on a printed impression of the subject matter involved. If, as illustrated in Figs. 3 and 7, the details are to be added after the impression has been attached to the flat back surface 29 of the mold, an offset proof 43 is taken from the original form 23 preferably on manila paper and cemented, printed side outward, onto the back of the mold with the different printed areas located with the aid of calipers or the like in proper register with the corresponding parts of the mold surface. The indentations 41 corresponding to the "solid" areas are then formed and located by taking a second offset proof 44 on paper of the required thickness and cutting out the proper parts so as to leave indentations of the proper depth when the second proof is pasted onto the first one with the corresponding parts in proper register. Then, the patches 42 are cut out from additional proofs or plain paper and pasted on the proof 44 or directly on the proof 43 in case there are no "solids" to be emphasized. By building up the make-ready details on the separate proof 43, location of the details regardless of their shape is facilitated.

The cost of the make-ready treatment can be reduced still further by building up the underlay 40 as a separate unit in a special department of the printing shop. To this end, a direct proof 47 (Fig. 12) is taken from the original 23 on heavy manila paper. A second similar proof 48 cut out to form the indentations 41 corresponding to the "solid" areas is then pasted onto the proof 47 with the corresponding printed parts in register. Then patches 42 are added for the "high light" areas. The underlay thus formed is trimmed to the proper size so that when its edges are matched with those of the mold 24 with the patches 49 lying against the back surface 29 of the mold, the printed parts will register accurately with the corresponding cavities of the mold. In the assembly of the parts for the molding operation, an underlay of this character would be placed printed side up on the lower press platen 31 and the mold laid thereon as shown in Fig. 8, these parts being retained in proper matched relation by the bearers 35 or other suitable guides.

The method above described for treating the plates to incorporate make-ready therein automatically in the molding operation is especially advantageous in that it avoids individual treatment of the several plates which are ordinarily made from a single engraving in the larger printing shops. This advantage results from association of the make-ready details with the mold from which any number of plates may be made. No additional equipment is necessary, and no special skill is required in forming and locating the make-ready details all of which operations may be performed outside of the press room. Manufacturing costs are thus reduced substantially as compared with methods ordinarily used in making printing plates ready for printing.

By constructing and molding printing plates as above described, it will be observed that a high degree of accuracy may be obtained in spacing the printing surfaces from the back of the carrying sheet 12 and in maintaining true parallelism 5 therewith. Owing to the thinness of the sheet and the resin layer in which the types are molded, the plate possesses sufficient flexibility to respond, under the pressure used in printing, to make-ready details located between the sheet 12 and 10 the backing plate 17, 18. In this way, any additional corrections that may be required to make the plate ready for printing may be applied readily.

Where the printing plate is to be used for prolonged runs in the printing press, it is sometimes desirable to provide a printing surface which is more resistant to wear and the action of the inks than a surface composed wholly of the synthetic resins now available. To adapt the 20 plate for such severe use, the surface of the plate including type projections in the resin layer 11 may be covered with a thin metallic shell 45 (Fig. 11) approximately .005 of an inch in thickness. This may be of any metal desired such as 25 chromium electrodeposited on the mold 24 prior to the molding operation which is carried on without removing the shell from the mold, the parts first being arranged as shown in Fig. 10 after which the heat and pressure is applied in the 30 manner above described. After molding, the plate assembly is stripped from the mold and the side edges 46 of the shell bent around the flanges 20 to form a unitary plate which may be attached to the press cylinder in the same manner as the 35 resin surfaced plate first described.

I claim as my invention:

1. For use in reproducing from an original type form a printing plate comprising type areas of molded resin adhering to a metal carrier sheet, the method which comprises forming a mold from said type face, covering said mold face with a layer of moldable material, placing said carrier sheet over said layer with a parting medium interposed therebetween to expose said material 40 to areas of said sheet corresponding in size and shape to the type indentations in said mold, applying pressure to said mold and carrier sheet whereby to cause setting of said material with the molded type areas only adhering to said 45 carrier sheet, and stripping off said parting medium and the material adhering thereto.

2. The method of making a printing plate reproduction of an original form type surface which comprises forming a mold from said type face, 55 making a printed proof of said form on a paper sheet, cutting out the printed areas from said sheet, applying a layer of resin ingredients to the indented face of said mold, placing said paper sheet on said resin layer with the cut-out portions matching with the corresponding type areas of said mold, heating said resin layer to a molding temperature, and pressing said resin layer and said proof sheet between said mold and a carrier sheet whereby to cause only the resin 60 opposite said cavities to adhere to said carrier sheet, and stripping off said paper sheet and the resin adhering thereto.

3. For use in making a printing plate comprising a molded resin layer on a sheet of metal having a surface treated for the adherence of plastic resin thereto, the method which comprises forming a metal surfaced mold having cavities therein corresponding to the type to be molded, masking the portions of said treated surface corresponding 70 to the type areas of the mold, applying a resin 75

to the non-type areas of said mold, covering the face of said mold with a layer of resin ingredients, locating said sheet with the exposed treated surface thereof in register with the type areas of the mold, pressing said mold and sheet together with said ingredients heated to a molding temperature, and stripping the resin off from the masked areas of said sheet.

4. For use in making a printing plate comprising a molded resin layer on a sheet of metal having a surface treated for the adherence of plastic resin thereto, the method which comprises forming a metal surfaced mold having cavities therein corresponding to the type to be molded, masking the portions of said treated surface corresponding to the non-type areas of said mold, and press-

ing a layer of resin ingredients between the face of said mold and said sheet whereby to mold the type on the exposed areas of sheet.

5. The method of forming a printing plate which comprises forming a mold having cavities therein corresponding to the type to be formed, covering the face of the mold with moldable material, covering said material with a carrier sheet having selected portions thereof corresponding to the type areas of said mold adapted for the adherence of the molded material thereto, and the remaining areas adapted for the non-adherence of the molded material and molding said material in said mold under pressure.

ARTHUR B. DAVIS. 15
